UNITED STATES PATENT OFFICE.

ALBERT L. BRUEGEMAN, OF NEWARK, NEW JERSEY.

STEAM BOILER.

Application filed April 14, 1921. Serial No. 461,833.

To all whom it may concern:

Be it known that I, ALBERT L. BRUEGEMAN, a citizen of the United States, and a resident of the city of Newark, county of Essex, and State of New Jersey, have invented a new and useful Improvement in Steam Boilers, of which the following is a full, clear, and exact description.

My invention relates to improvements in steam boilers of the water tube variety, and the general object of my invention is to make a boiler of this class which has a higher efficiency than boilers hitherto made. More particularly my invention is intended to produce a boiler in which the generating and circulation tubes are in the hottest part of the furnace gases, and in which a storage reservoir is arranged and connects with the drums of the generating part of the boiler, so that there is an unusually large factor of safety, and the storage reservoir will supply water for circulation and steam generation in such ample capacity that there will be no danger of burning out the tubes and destroying the boiler. My invention is further intended to construct, arrange, and connect this storage reservoir with the generating parts of the boiler, so that the feed water will be supplied to the reservoir in its coolest parts, the upper part of the reservoir can be utilized as a steam dome, and the water of circulation will pass through the main chamber of the reservoir, while the gases of combustion will pass around it, and so that water in the storage reservoir will be heated and delivered at the boiling point to the generating parts of the boiler. My invention is further intended to arrange the pre-heating parts of the water in such a way that the lime and other scale forming materials will be separated by heat and collected in a way to be readily blown off, and also to arrange the reservoir so that the water, as it is fed to the generating parts of the boiler, will be broken up under heat, and the air freed and mingled with the steam, and thus the air will pass out and not have any injurious and corrosive action on the boiler parts.

My invention is further intended to produce a boiler in which the circulation is exceedingly free and ample, and in which the water as it circulates will be exposed to the hot gases of combustion of the furnace, so as to practically absorb all the heat thereof.

In general my invention is intended to make a better, simpler, safer, and more efficient boiler of the water tube class than has heretofore been produced.

Reference is to be had to the accompanying drawings forming a part of this specification, in which similar reference characters indicate corresponding parts in the view.

The figure is a central vertical section of the boiler showing my improvements.

The drawing is by way of example, and shows a single boiler element which will be described in detail, and it will be understood that a battery of these elements can be combined to produce larger steam units if desired.

The generating part of the boiler comprises essentially the upper and lower drums A and B, which are spaced apart and connected by a bank of tubes C, which are inclined and exposed to the hottest gases of combustion. The upper part of the drum A serves as a steam chamber, and the lower part carries hot water.

The water is supplied to the drums A and B from a vertically arranged reservoir D which is preferably cylindrical, and which is divided by the spaced apart tube plates H into three principal compartments, the upper P serving as a steam dome, the middle portion M as a water reservoir, and the lower chamber U connecting through the nipple G with the lower drum B. The drum A connects by horizontal pipes F which are arranged below the water line with the lower part of the steam drum P, and the upper part of the drum A, or steam chamber, connects by the pipes E with the steam carrying part of the chamber P. Tubes K extend from the upper plate H through the corresponding lower plate, and serve to carry the water of circulation.

The middle chamber M of the reservoir D has an outlet opening J extending from the upper plate H into the steam drum, and arranged around this in step fashion are plates O which as the hot water rises through the pipe J and overflows the plates, serve to break up the hot water, and free the air which mingles with the steam.

It will be seen from the foregoing description that the circulation is as follows. From the drum A, the water passes through the pipes F to the lower part of the steam drum

P, thence downward through the tubes K, thence through the nipple G to the drum B, and thence through the generating tubes C back to the drum A. Thus a very easy and natural flow of circulation is provided, and it will be observed that the hot water passing downward through the tubes K will serve to heat the water in the storage reservoir D, and this water will also be heated by the flue 10 gases which pass around the outside of the reservoir.

The boiler setting can be of any approved or conventional type, but I have shown an arrangement which lends itself to the easy generation of steam, and in which the gases of combustion are utilized to the best advantage. The furnace 10 has an upward extending inclined flue 11 delivering to the chamber 12 in which is the super heater 13. I have shown a conventional super-heater, and any suitable type can be used. In the flue 11 and dividing the bank of generating tubes C, is a diaphragm or baffle 14 which causes the hot gases to pass up on one side 25 of the baffle and down on the other, as indicated by the arrows. From the back of the furnace the hot gases pass upward in the flue 15 in which the reservoir D is located, over the vertical baffle 16 shown by dotted lines in 30 the drawing, and thence down and out through the discharge flue 17.

The reservoir D is provided with a vertically arranged supply pipe 18 for feed water which connects with a valve controlled water supply pipe 19, and leading from the lower part of the chamber M and out through the boiler setting, is a valve controlled blow-off pipe 20. By this arrangement it will be seen that the cold water enters the coldest part of the boiler, and that it rises in the reservoir and is heated as already described, and this heating at rather high temperature, serves to separate and deposit the lime and scale making materials which collect on the lower plates H, and can be blown off when desired through the pipe 20. It will be noticed that the water will rise hot through the pipe J, be broken up over the plates O, and the air separated as already described, and it will be seen that the flow of the intake water in the chamber B is in one direction, while the flow of circulating water is in the opposite direction, and further that the water as it passes to the boiler, and to the hottest part thereof, follows the flow of combustion gases, but in the reverse direction, so that these gases are utilized to the best possible advantage in the generation of steam.

It will also be seen that ample provision is made in the storage reservoir D for keeping the generating parts of the boiler well supplied, and thus a larger safety factor is provided which even if the fireman is negligent, will prevent any accident to the boiler.

It will be further seen that the invention provides a very simple and efficient boiler construction, and that as above stated, the units shown can be multiplied into a battery of any desired number of units, if a larger steam plant is desired.

I claim:

1. A steam boiler comprising upper and lower drums, a bank of tubes connecting said drums, and a reservoir having a steam dome at the top, a storage compartment beneath it, and a bottom compartment beneath the storage compartment, tubes connecting the upper and lower compartments of the reservoir, water tubes connecting the upper drum and the steam dome below the water level, tubes connecting the upper part of the upper drum with the steam dome, and a connection between the lower compartment of the reservoir and the lower drum.

2. A steam boiler comprising a generating part consisting of upper and lower drums spaced apart, and a bank of tubes connecting the drums, said tubes being arranged in the up-draft part of the furnace, a separate down-draft flue connecting with the up-draft part of the furnace, a storage reservoir contained in the down-draft and with its upper and lower parts connecting with the aforesaid drums, and circulation pipes also connected with the drums and passing through the storage part of the reservoir.

3. A steam boiler comprising upper and lower drums spaced apart and connected by generating tubes, a reservoir connected with both drums and provided for circulation and a feed water supply, said storage reservoir having a steam dome at the top, a vertically arranged pipe extending from the reservoir into the steam dome, and means for breaking up the water and freeing the air as it overflows said pipe.

4. A steam boiler comprising a generating portion consisting of spaced apart drums and generating tubes connecting them, a storage reservoir having a steam dome at the top, and a storage portion in the middle part thereof, water connections between the upper and lower parts of the reservoir and the upper and lower drums, circulation pipes extending vertically through the storage part of the reservoir, and a pipe leading from the upper part of the storage chamber of the reservoir to the steam dome.

5. A steam boiler comprising a generating portion having upper and lower drums spaced apart and generating tubes connecting them, a reservoir having upper and lower chambers connected with the upper and lower drums and an intermediate water storage chamber, means for heating the water in the storage chamber, and a blow-off pipe opening from the lower part of said storage chamber.

6. A steam boiler comprising a generating portion consisting of upper and lower drums spaced apart and generating tubes connecting them, a storage reservoir having upper and lower chambers connected with the upper and lower drums and an intermediate chamber for the storage of a water supply, circulation pipes connecting the upper and lower chambers of the reservoir and serving to heat the water in said reservoir, and a blow-off pipe opening from the lower part of the storage chamber of the reservoir.
7. A steam boiler comprising upper and lower drums spaced apart and connected by generating tubes, a storage reservoir having an upper steam chamber, a lower chamber, and an intermediate water storage chamber, upper and lower chambers having connections with the upper and lower drums, circulation tubes extending through the middle or storage chamber of the reservoir, a feed pipe extending from the upper part of the reservoir into the steam dome, and a water
- supply pipe discharging into the lower portion of the water chamber of the reservoir.
8. A steam boiler comprising a generating portion having upper and lower drums spaced apart and connected by generating tubes and exposed to the hottest spaces of the boiler furnace, a vertically arranged storage reservoir supported in a flue of the furnace and having upper and lower chambers connected with the aforesaid upper and lower drums, and a middle chamber for the storage of water, a water supply pipe discharging into the middle chamber of the reservoir, circulation tubes connecting the upper and lower chambers of the reservoir, and a pipe leading from the storage chamber of the reservoir into the steam dome thereof.
